UNITED STATES PATENT OFFICE

EDMOND G. DUPREE, OF RICHMOND HILL, NEW YORK, ASSIGNOR TO BOORUM & PEASE COMPANY, OF BROOKLYN, NEW YORK, A CORPORATION OF NEW YORK

SHIFTING DEVICE FOR PRONG BINDERS

Application filed December 4, 1930. Serial No. 500,093.

This invention relates to devices for shifting loose leaves in prong binders in cases where the leaves are of less height than the height of the binder, and are filed in the binder in overlapping relation with an edge of each sheet visible.

An object of the invention is to provide an improved shifter which is convenient to operate and economical to manufacture. 10 Another object is to provide a shifter which is separate from the binder and can be used in the ordinary commercial binder.

In the drawings,

Figure 1 is a partial end view of a prong binder closed and with the leaves partly in section.

Figure 2 is an end view of the prong binder open showing the improved shifting device in solid lines in one position, and in dotted 20 lines in another position in the binder.

Figure 3 is a perspective view of the shifting device.

Figure 4 is a partial plan view of a prong binder open and showing the shifting device 25 in operation. The shifting device is shown with the handle partly broken away.

In the drawings the binder with which the shifter is shown contains the usual prongs 10 and 11 having tapered free ends, supported 30 by back elements 12 and 13 respectively. Sheets or leaves 14 are threaded upon the prongs in overlapping relation with a margin of each visible as shown in Fig. 4. Near a margin of each sheet are a plurality of perforations 15, all equally spaced from center to center. The prongs are spaced apart by multiples of the distance between perforations.

The improved shifting device 16 is free or 40 detached from the binder, and is free to slide along the entire length of the back element 13. When the binder is open the lower edge of the shifter is adapted to rest against a stop provided on one of the back members. As 45 illustrated this stop consists of an angle formed by a wall 17 extending longitudinally along the back member 13 and protruding approximately at right-angles to that part of the back member which carries the 50 prongs. Other forms of stops could be used.

The shifting device comprises a plate 18 having a plurality of perforations 19 arranged longitudinally or horizontally thereof, a plurality of perpendicularly projecting pins 20 arranged in a row longitudinally 55 thereof and spaced transversely from the perforations, and a rearwardly projecting flange 21, which forms a convenient handle at the top of the shifter. In the drawings the pins are shown as located vertically above 60 certain of the perforations.

The perforations 19 are preferably spaced apart by a distance equal to that between the perforations 15 of the sheets. Each perforation 19 is large enough to receive the tapered 65 end of a prong but not large enough to admit the rest of the prong.

The pins 20 are shorter than the prongs and have their ends recessed to receive the tips of the prongs. The pins are spaced apart by 70 a distance equal to the distance between perforations 15 in the sheets, or multiples thereof, the smallest distance between two pins being equal to the distance between two perforations, and the greatest being equal to the distance between two prongs 10 on one side of the binder. Various numbers and spacings 75 of the pins may be used.

The perforations 19 are spaced from the bottom of the shifting device a suitable distance so that when the binder is open and the bottom edge of the device rests in the angle between the wall 17 and the adjacent side of one of the back elements, the tips of the prongs 11 on the same back element, can 80 lie in the perforations 19, as shown in solid lines in Fig. 2. The pins 20 are of suitable length and are suitably spaced with relation 85 to perforations 19, so that when the shifter is swung from the position just described 90 toward the other back element, it will leave the prongs 11 and the tips of the prongs 10 on the other back element will nest in or register with the ends of pins 20, as shown in dotted lines at 20a in Fig. 2. If a stop is 95 provided in a different location from that illustrated, the relative location of the pins and perforations may be varied to secure the register of the pins with the prongs on one side of the binder, and the register of the 100

perforations with the prongs on the other side of the binder.

The shifting device is used to advantage when it is desired to transfer from one set of prongs to another set, a sheet filed in the binder at any point other than the top of the pile of sheets, without disturbing the relation of certain sheets to each other.

For example, if it is desired to shift sheet 14a keeping the same relation between it and the sheets 14b, (see Figs. 2 and 4) the binder is opened leaving all the sheets on prongs 10 on the right side. The shifter is inserted with its bottom edge resting against the stop, 15 and is slid along longitudinally of the binder until two or more of the pins 20 are opposite prongs 10 upon which sheet 14a is threaded and certain of the pins 20 are also opposite prongs 10 upon which sheets 14b 20 are threaded. The shifter is then placed in the position shown in dotted lines in Fig. 2, with the tips of prongs 10 lying in the ends of pins 20a. Sheet 14a and all the sheets 25 14b are now transferred to pins 20 or 20a, the shifter is swung free of the prongs 10 and is slid longitudinally along the back element 13 until the pins 20 bearing the sheets 14a and 14b are opposite the prongs 10 to which it is desired to transfer those sheets. The 30 shifter is again swung toward prongs 10, until the tips of prongs 10 to which the sheets are to be transferred nest in the ends of the pins 20 which carry the sheets, and the sheets are transferred to the prongs 10 in the new 35 location, reversing the direction of the arrow in Fig. 2.

If while shifting the sheets it is for any reason desired to leave them temporarily upon the shifter, the shifter can be swung to 40 the position shown in full lines in Fig. 2, with the tips of prongs 11 registering with the perforations 19. The shifter will remain temporarily either in this position or in the position shown in dotted lines in Fig. 2, 45 without being held by the operator.

When the transferring of sheets from one position to another has been completed, the shifter may be removed and the binder closed.

50 I claim:

1. A shifter for loose leaf prong binder, comprising a plate having a longitudinal series of perforations and a plurality of pins attached to the plate and spaced transversely 55 from the series of perforations.

2. A shifter for loose leaf prong binder, comprising a plate having a longitudinal series of perforations, a plurality of pins attached to the plate and spaced transversely 60 from the series of perforations and a flange along the top edge of said plate, forming a handle.

3. A loose leaf prong binder having a pair of back elements each bearing prongs and 65 one of said back elements having a stop, in

combination with a detached shifter adapted to rest against said stop and being adapted to slide longitudinally the length of the back element.

4. A loose leaf prong binder having a pair 70 of back elements each bearing prongs and one of said back elements having a stop, in combination with a detached shifter adapted to rest against said stop, said shifter comprising a plate having a longitudinal series 75 of perforations to register with the prongs on one back element, and a plurality of pins carried by said plate and spaced transversely from the series of perforations.

5. A loose leaf prong binder having a pair 80 of back elements each bearing prongs and one of said back elements having a stop, in combination with a detached shifter adapted to rest against said stop, said shifter comprising a plate having a series of longitudinal 85 perforations to receive the tips of prongs on one back element, said perforations being too small to admit the rest of said prongs, and a plurality of pins having recessed ends carried by said plate and adapted 90 to receive the tips of the prongs on the other back element.

6. A shifter for use in a prong binder having sheets with perforations along one margin in combination with a pair of back elements each bearing prongs spaced apart by multiples of the distance between said perforations, said shifter comprising a plate having a longitudinal series of perforations to register with prongs on one back element of the binder and a plurality of pins attached to the plate to register with prongs on the other back element of the binder. 95

7. A shifter for use in a prong binder having sheets with perforations along one margin in combination with a pair of back elements each bearing prongs spaced apart by multiples of the distance between said perforations, said shifter comprising a plate having a longitudinal series of perforations to register with prongs on one back element of the binder and a plurality of pins attached to the plate to register with prongs on the other back element of the binder, the perforations in the shifter being spaced apart by distances equal to the distance between perforations in the sheets, and the pins being spaced apart by the same distance or by multiples of the same. 110

8. A shifter for use in a prong binder having sheets with perforations along one margin in combination with a pair of back elements each bearing prongs spaced apart by multiples of the distance between said perforations, said shifter comprising a plate having a longitudinal series of perforations to register with prongs on one back element of the binder and a plurality of pins attached to the plate to register with prongs on the other back element of the binder, the perforations 120
